[57] CLAIM

The ornamental design for a napkin dispenser, as shown
and described.

DESCRIPTION

FIG. 1 is a perspective view of a napkin dispenser showing
my new design, the napkins shown in broken lines
for illustrative purposes only;

FIG. 2 is a top plan view thereof;

FIG. 3 is a front elevational view thereof;

FIG. 4 is a side elevational view thereof, the opposite
side being a mirror image thereof;

FIG. 5 is a bottom plan view thereof; and,

FIG. 6 is a back elevational view thereof.

FIG. 1

FIG. 2

FIG. 3

FIG. 4

FIG. 5

FIG. 6
